NEON TUBE CONNECTOR

Frederick J. Hensler, Concord, N. Y.

Application December 20, 1939, Serial No. 310,092

5 Claims. (Cl. 173—328)

This invention relates to devices for connecting the ends of neon tubes and comprehends an improved device of this character which establishes both electrical and mechanical connection between the ends of adjacent tubes or between the source of electrical current and the end of a tube, and which also serves to house and protect the exposed terminals of the tube electrodes against short circuits resulting from rain, snow or sleet, while excluding dust, dirt or other foreign matter which may tend to foul the same.

The invention comprehends an improved connector of the indicated character which embodies a housing fashioned from a non-combustible insulation material possessing the requisite strength and durability and enclosing an element by means of which electrical connection between the ends of adjacent tubes or between the source of electrical current and a tube end may be expeditiously and effectually established without the necessity of employing tools or requiring the services of specially trained operatives.

Other objects of the invention reside in the provision of a connector and housing for the ends of neon tubes which embodies but few and simple parts capable of being economically produced and assembled.

With the above enumerated and other objects in view, the invention is set forth in detail in the following specification and accompanying drawing, in which:

Fig. 1 is a perspective view of a connector and housing device operatively connecting the ends of adjacent neon tubes.

Fig. 2 is an enlarged longitudinal sectional view therethrough.

Figs. 3 and 4 are enlarged perspective views of the housing sections detached and separated from each other.

Fig. 5 is an enlarged perspective view of the electrical connecting means removed from the housing.

Fig. 6 is a longitudinal sectional view through a housing device and means of connection between a source of electrical current and an end of a neon tube.

Referring to the drawing by characters of reference, A and B designate respectively portions of adjacent neon tubes which are respectively formed of reversely bent ends C and D having the exposed electrical terminals E and F. The connector includes a housing fashioned from a non-combustible insulation material such as glass, glazed porcelain, porcelain or plastic materials and consists of a body section 10 and a 55

cap section 11 which are of tubular formation respectively provided with the closed ends 12 and 13 and open at the opposite ends.

The body section 10 is formed with a neck 14 of reduced diameter adapted to fit within the enlarged recessed end 15 of the cap 11 and said neck is provided with an external thread 16 adapted to engage within the internal thread 17 of the recessed end 15 of the cap to detachably connect the housing sections 10 and 11.

An annular sealing gasket 18 surrounds the neck 14 and is disposed between the sections to seal the same at their juncture. The body section 10 of the housing is formed with a notch 19 and extends longitudinally thereof inwardly from the outer end of the neck and into the main body portion thereof and which notch communicates with the bore 20 of the section. The notch 19 is adapted to receive therethrough the bight portions of the reversely bent ends C and D of the neon tubes A and B, it being understood that the end C of the tube A extends axially of the bore 20, while the end D of the tube B extends axially of the bore 21 of the cap 11. The notch 19 is of greater width than the diameter of the neon tubes and in order to fill the space between the bight portions of the neon tube ends and the notch, yieldable plugs 22 and 23 of sponge rubber or an equivalent material are fitted over the bight portions in surrounding relation thereto and are compressed between the walls of the notch and between each other and the bight portions. This mechanically connects the tubes and houses the reversely bent ends C and D thereof.

The tubes are electrically connected to each other by means of a conductor element which consists of a straight length of resilient wire 24 having coiled contractile ends 25 and 26, the convolutions of which are of a diameter to telescopically receive the reversely bent ends C and D of the tubes with the endmost coils having inwardly spiraled extremities 27 and 28 to effectually engage with the exposed terminals of the tube electrodes. It will be understood that the distance between the spiral extremities 27 and 28 of the end convolutions under the normally contracted arrangement of the coiled ends 25 and 26 will be less than the distance between the terminals E and F when the tubes are arranged in the housing so as to expand the coiled ends 25 and 26 and place them under a tension to thereby insure and maintain proper electrical contact of the terminals E and F with the spiral portions 27 and 28.

As illustrated in Fig. 6 of the drawing, the connector, in this instance, is designed for establishing mechanical and protected electrical connection between a source of electrical current and the end of a neon tube. The housing, in this instance, is substantially identical with that previously described, except that the closed end 12 of the section 10 is provided with an aperture 30 having a tubular nipple 31 extending therethrough formed with a headed inner end 32 and an externally threaded outer end 33 engaged by a coupling collar 34 by means of which a conduit 35 is connected with the body section 10. An insulated conductor wire 36 leading from a source of electrical current, extends through the conduit 35 and through the nipple 31 into the body section 10 and the exposed end of said conductor wire is secured by a bolt or other fastening means 37 to a conductor element 24 having a spiral terminal 38, the outer convolution 39 of which is snapped into an internal annular groove 40 formed in the body section 10 and maintained in place in said groove by the inherent expansive action of the convolution 39. The conductor element 24 is formed with the opposite coiled end 26 and is connected with the reversely bent end D of the neon tube B.

What is claimed is:

1. In a connector for neon tubes having reversely bent ends provided with exposed electrode terminals, a housing of non-combustible insulation material including a pair of tubular sections each having a closed outer end and telescopically engaged open inner ends axially interfitted one within the other, one of said sections having a notched inner end for receiving the reversely bent ends of adjacent tubes, and a contractile conductor means located within said housing and contacting respectively the electrode terminals of the reversely bent tube ends for establishing electrical connection therebetween.

2. In a connector for neon tubes having reversely bent ends provided with exposed electrode terminals, a housing of non-combustible insulation material including mating tubular sections each having a closed outer end and telescopically engaged open inner ends axially interfitted one within the other, one of said sections having a notched inner end for receiving the reversely bent ends of adjacent tubes, and a conductor means located within said housing and contacting respectively the electrode terminals of the reversely bent tube ends for establishing electrical connection therebetween, a yieldable elastic gasket surrounding the juncture of said tube ends with the tubes and positioned to cooperatively

engage with each other and the walls of the notch to seal the space therebetween.

3. In a connector for neon tubes having reversely bent ends provided with exposed electrode terminals, a conductor element having coiled contractile opposite end portions adapted to respectively receive the reversely bent ends of adjacent neon tubes, the outermost convolutions of each end portion having an inwardly spiraled extremity with which each of the exposed electrode terminals contact, and a housing of non-combustible insulation material including mating tubular sections each having a closed outer end and open telescopically engaged inner ends axially interfitted one within the other, one section having a notched inner end for receiving the reversely bent ends of adjacent tubes.

4. In a connector for neon tubes having reversely bent ends provided with exposed electrode terminals, a housing of non-combustible insulation material having an opening intermediate the ends thereof for receiving the reversely bent ends of adjacent tubes, yieldable elastic gasket means surrounding the juncture of the tube ends with the tubes and engaging with the walls of the opening to seal the space between the tubes and the wall of the opening, and a conductor located within the housing and including an inextensible intermediate portion and coiled contractile opposite end portions having open inner ends and closed outer ends, said contractile end portions being telescopically disposed over the reversely bent ends of adjacent neon tubes with the ends of said tubes extending into the inner open ends of the coiled portions and abutting against and electrically connected with the closed outer ends thereof so as to expand the coiled portions outwardly to place the same under tension to maintain the electrical connection.

5. In a connector for neon tubes having reversely bent ends provided with exposed electrode terminals, a housing of non-combustible insulation material having an opening intermediate the ends thereof for receiving the reversely bent end of a neon tube, and a conductor located within the housing and including an inextensible portion and a coiled end portion having an open inner end and a closed outer end and within which the reversely bent end of the tube extends with the electrode terminal at the outer end of the tube engaging with the outer closed end of the coiled portion so as to expand the coiled portion outwardly to place the same under tension to maintain the electric connection therewith.

FREDERICK J. HENSLER.
